Primary Examiner — Patricia A Palasik

(57) **CLAIM**

The ornamental design for a carrying unit of a warehousing robot as shown and described.

DESCRIPTION

FIG. 1 is a front view of a carrying unit of a warehousing robot embodying my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof from above and to the left; and,

FIG. 8 is a second perspective view thereof from below and to the right.

The broken line portions of the carrying unit of warehousing robot in the drawings from no part of the claimed design.

1 Claim, 8 Drawing Sheets
